UNITED STATES PATENT OFFICE

2,599,006

UNIVERSAL TYPE SPRING-PRESSED
BINDING POST

Albert Nicholas Andrea Melchior, London, England, assignor to A. C. Cossor Limited, London, England, a company of Great Britain

Application February 24, 1948, Serial No. 10,487
In Great Britain November 20, 1945Section 1, Public Law 690, August 8, 1946
Patent expires November 20, 1965

2 Claims. (Cl. 173—259)

1

This invention is concerned with terminals of the type adapted to permit of the detachable connection of electrical leads.

Among the objects of the invention are effective insulation of the conducting parts of the terminal from the user during normal handling and provision for alternative methods of connecting a lead to the terminal or for connecting more than one lead thereto at a time.

In accordance with the invention from one of its aspects an electrical terminal has a conducting core which is at all times located wholly within an insulating sleeve and which is engageable both by a crocodile clip or the like inserted into the open end of the said sleeve and by a lead wire inserted through a peripheral aperture in the sleeve into an aperture in the core when the sleeve is displaced against spring pressure to bring the apertures into alignment. The conducting head of the terminal is thus sunk considerably within the sleeve where it is shielded from chance contact whilst the projecting part of the sleeve also serves to support the crocodile clip laterally.

In accordance with the invention from another aspect, an electrical terminal comprises a conducting core having a transverse aperture therein, an insulating cup fixedly carrying said core and adapted to be secured to a panel or the like support, an insulating sleeve at all times surrounding the whole of that part of the core upstanding above the rim of said cup and slidably but non-rotatable on the core so that on depression of the sleeve towards the cup a peripheral aperture therein is brought into register with the aperture in the core, and a spring between said cup and said sleeve urging the sleeve upwards from the cup.

The following description relates to the accompanying drawing in which Figure 1 is a side view partly in section of an embodiment of the invention and Figure 2 is a top plan view.

The base is in the form of an insulating cup 11 within the cylindrical side wall of which the bottom end of an insulating sleeve 12 is a free axially sliding fit. This sleeve is formed with an interior annular flange 13 somewhat more than half way up its bore, the under side of which flange acts as a seat for the top of a coiled compression spring 14 bearing at its bottom end on the bottom of the cup base 11.

The conducting core of the terminal is a metal part 15 having a screwed shank 16 which engages in an axial hole in the bottom of the cup 11 and, when home, extends sufficiently beneath it for

attachment purposes. The body 15 of the core is of a diameter such that the coil spring 14 is accommodated freely in the tubular space between the said body 15 and the sleeve 12 and as substantially to fill the section beneath the aforementioned interior flange 13 of the latter. Under the influence of the spring 14 this flange 13 is normally held in abutment against an outward flange 17 around the top of the core body 15 which thus acts as a stop limiting the upward travel of the sleeve 12.

The top of the core 15 is formed or provided with an axially disposed terminal portion in the form of a collar-stud head 18, which is normally surrounded by the upper part of the sleeve 12 i. e. that above the flange therein, which part should extend some way above the head, preferably so far that even when the sleeve 12 is fully depressed i. e. with its bottom end in contact with the base 11, the head 18 does not project substantially above the top edge of the sleeve 12. Thus portion 18 of reduced diameter is adapted to be gripped by a spring clip inserted through the open end of the sleeve 12. This upper part of the sleeve 12 is also formed with a pair of diametrically opposite holes 19 which when the sleeve sits and in register with a transverse hole 20 through the body 15 of the core. In order to prevent rotation of the sleeve 12 about the core 15 (which would of course interfere with such registration) the body of the core is formed with flats 21 and the shape of the inner flange 13 of the sleeve adjusted to change the section within the flange correspondingly. The outer surface 35 of the upper part of the sleeve 12 is knurled at 22 to facilitate manipulation. The terminal is fixed upon a panel 23 by means of a nut 24 engaging a screw-thread upon the base 11.

The construction of terminal thus described, is very well shielded with external insulation and permits of ready engagement either by a plain lead or by one carrying a crocodile clip or by both simultaneously. Moreover it is simple, robust and easily assembled.

I claim:

1. An electrical terminal comprising an insulating cup, a conducting core upstanding from the base of said cup and having a laterally extending flange at the upper end thereof and being apertured transversely near the upper end thereof, an axially movable, open-ended, insulating sleeve surrounding said core and said laterally extending flange and having one end projecting within said cup, said laterally extending flange being formed to have a reduced

transverse dimension in one direction to provide sufficient clearance between it and said insulating sleeve to allow the attachment of a spring clip inserted through the adjacent open end of said sleeve, said sleeve being longer than the upstanding portion of said core and being transversely apertured near the upper end thereof, an internal flange formed below said aperture in said sleeve and surrounding said core below said laterally extending flange and being adapted to abut said laterally extending flange to limit the upward axial movement of said sleeve, and a compression spring surrounding said core, having its lower end seated in said cup and its upper end bearing against said internal flange, and urging said internal flange into abutment with said laterally extending flange.

2. An electrical terminal comprising an insulating cup, a conducting core upstanding from the base of said cup and provided at the upper end thereof with a terminal portion of reduced transverse dimension adapted to be gripped by a spring clip, said core being apertured transversely at a portion near said upper end and being provided with a laterally extended flange disposed between said transversely apertured portion and said terminal portion, an open-ended insulating sleeve surrounding the upper portion of said core including said laterally extending flange and said terminal portion and having its lower end projecting within said cup, the upper end of said sleeve being adapted for

5 permitting insertion therein of said spring clip to grip said terminal portion of reduced transverse dimension, said sleeve extending above the upper end portion of said core and being transversely apertured near the upper end thereof, an internal flange formed below said aperture in said sleeve and surrounding said core below said laterally extending flange and being adapted to abut said laterally extending flange to limit the upward axial movement of said sleeve, and a compression spring surrounding said core, having its lower end seated in said cup and its upper end bearing against said internal flange, and urging said internal flange into abutment with said laterally extending flange.

10 15 ALBERT NICHOLAS ANDREA MELCHIOR.
